UNITED STATES PATENT OFFICE.

JOSHUA TERRY JACKSON, OF TEXARKANA, TEXAS.

COMPUTING-MACHINE.

No. 893,628.

Specification of Letters Patent. Patented July 21, 1908.

Application filed July 11, 1907. Serial No. 383,183.

To all whom it may concern:

Be it known that I, JOSHUA TERRY JACKSON, citizen of the United States, residing at Texarkana, in the county of Bowie and State 5 of Texas, have invented certain new and useful Improvements in Computing-Machines, of which the following is a specification.

My invention relates to computing machines and has particular reference to that 10 class of appliances which are designed to be operated by a stylus, or the fingers and in which provision is made for a temporary recording of results, no printing mechanism being supplied.

15 The chief objects of my improvements are to provide a combined adding and subtracting machine that is simple in construction, easily understood, and, having few parts, will not readily get out of order, the simplicity of its construction rendering it capable of being economically manufactured so that it can be sold for a comparatively small price; to supply a computing machine having such form and dimensions that it can be 20 readily carried from place to place, and when desired may be arranged in juxtaposition with the columns of figures on a sheet or page, thus facilitating the work of the accountant to a marked degree; and to furnish a combined adding and subtracting device in 25 which the manual movements for the different computations will be identical, thus avoiding the tendency to confusion which will result when the required motions are 30 reversed, as is usual in devices of this class.

Further objects of my invention are to 35 provide means for readily differentiating the groups or places for the figures, by means independent of their relative position; and 40 to supply mechanism for preventing the displacement of the indicating members when once set, avoiding errors from the momentum imparted to said members, and to lock the latter in position so that they will remain 45 immovable under ordinary manipulations of the device, and especially when reversing the instrument, which is required when changing from one form of computation to another.

50 I accomplish the above and other important results by the employment of an apparatus which consists, generally speaking, of a flat rectangular case, in which are arranged in parallel a series of alternately fixed and 55 movable bars, the fixed bars having the numerals 1 to 9 impressed upon their upper

faces in regular columns, thus constituting a key board, which is visible in an interval in the casing, and the sliding bars having spaced abutments corresponding with the 60 said numerals, by means of which the said bars can be reciprocated through the medium of the pencil or stylus point in either direction, suitable sight holes being provided to permit inspection of indicating figures which 65 are carried by said sliding bars. The periods or columns are read downward, instead of from left to right, the slideable bars representing the orders or periods, beginning with the lowest slide which is regarded as units, or 70 when considered decimal would be regarded as hundredths. As an aid in the mnemonic process the slideable members are given contrasting colors, each group, or 75 period, having the same color, the right and left hand portions, however, being furnished with different depths of color; thus the left hand half of each bar has a dark color and the right hand half a lighter tint, thus little 80 mental effort being required to differentiate the two portions, and in a short time the mental process will become purely automatic.

In the accompanying drawing, which 85 forms a part of this specification:—Fig. 1 is a plan view of my improved computing machine; showing the side arranged for adding; Fig. 2 is a plan view of the reverse side, used in subtraction, a portion of the casing being broken away to disclose the method of 90 construction; Fig. 3 is a sectional view on the line 3—3 of Fig. 1; Fig. 4 is a perspective view of one of the fixed bars, and Figs. 5 and 6 are rear and front views, respectively, of 95 one of the slideable bars.

Referring to the drawing in detail, the 100 numeral characters 10, 10^a, indicate the side members and 11 the end pieces of a rectangular frame, oblong in shape and provided with a casing or side plates 12, which extend from the ends to approximately one third the length of said frame, thus leaving an interval in the center equal to about one third the area of the frame uncovered. This interval is occupied by a series of rectangular bars 13 placed parallel and spaced apart at equal intervals. These bars are somewhat longer than the space between the casing plates 12, and their ends are received between each pair of said plates and secured in position in any 105 convenient way. That portion of each bar exposed between the margins of the casing is 110

reduced in vertical diameter and supplied with spaced characters consisting of the digits from 1 to 9, so placed on the bars 13 that the said characters will fall in vertical columns when the parts are assembled and when so arranged constitute guides for properly locating the pencil or stylus during the computing processes, and hereinafter termed the keyboard. The rear face of each bar 13 is furnished with a longitudinal U shaped channel or groove 14 and the front face is supplied with a recess 15 to permit of adequate movement of a flat detent spring 16 secured at one end to the said bar and near the other is bent at an angle to form a projection 17 adapted to engage notches in the sliding members hereinafter described. Near one end of the reduced portion of each bar is a semi circular sight notch 18 formed by cutting away a portion of the upper rear corner of the bar. In the intervals between the said fixed bars 13 and the casing and the bars themselves, are located slidable members 19 of such length that when one end abuts against either end piece 11 of the frame, the other will extend beyond the opening between the casing plates. The anterior margin of each slide 19 is beveled to form an angular ridge or projection 20 adapted to be received in the rear groove 14 of the adjacent fixed bar 13. The frame member 10 also has a V-shaped groove 14^a formed upon its inner surface to receive the projection of the adjacent slide and its rear upper corner has a sight notch 18^a corresponding with the notches 18 in the fixed bars 13. The rear margins of the slides are provided with spaced notches 21 with which the projections 17 of the detent springs 16 yieldingly engage as the slides are reciprocated. The upper and lower faces of the said slides are provided with spaced lugs or flanges 22 which serve as abutments against which the stylus impinges to operate the slide in either direction. Upon the upper and lower surfaces of the projecting angular ridge 20 are impressed the ordinals 0 to 9. The ordinals 23 upon the upper surface are arranged from left to right, beginning at the extreme left, and the characters 24 upon the under surface are placed in the same order, but inverted when the slide is viewed as a whole, as shown in Fig. 6; when the slide is reversed the latter figures appearing right side up but reversed as to order, diminishing from left to right, which makes them available for the operation of subtraction, those upon the superior aspect being properly arranged for addition when that side is uppermost.

The key-board is alike upon both sides of the device and consequently the manipulation will be the same for either adding or subtracting.

The slide bars 19 represent the places or groups of figures; thus the lowest bar repre-

sents units, the second tens and so on, up to the highest, which in the illustration is carried to hundreds of millions as shown in Figs. 1 and 2, by the designations placed to the right of the key board. It is often convenient to consider the first two places as a decimal, especially in computing U. S. money, and to aid in locating the places under this system of notation the proper designations are placed to the left of the key board. To further assist the eye in determining the columns or places the first two slides, representing cents are colored upon the left in unison, in the instance given being designated as green, indicated by *a*. The units tens and hundreds of dollars are colored purple *b*, the thousands slides are tinted green, returning again to purple in the millions of dollars. The opposite portions extending from the median line to the extreme end, are supplied with a contrasting color, lighter in tint. Thus the decimal placers are colored white *c*, upon the right and the units, hundreds and thousands a light blue *d*, returning to white in the next period, and so on.

It will be seen that the arrangement of slides shown and illustrated will permit the ordinals imprinted upon the inclined surfaces of the projection 20 to be readily seen through the notches 18, which form the sight openings, as the figures are brought successively opposite to said openings during the sliding of the members 19 in the manner to be described.

The manipulation of the appliance is as follows for the process of addition: Supposing the slides to be all carried to the right until 0 appears at every sight notch and it is desired to add 6 dollars, 30 cents and 2 cents, a pencil or stylus is placed upon the slide corresponding with dollars against that lug which is opposite the figure 6 of the adjacent fixed bar 13 and the slide carried thereby to the left until the pencil strikes the margin of the casing plate which forms a stop therefor; the numeral 6 will then appear in the corresponding notch. The same procedure is repeated for 30 cents, the stylus or pencil being placed upon the second slide, and when this has been moved the units slide is moved two steps in the same manner, and 632 will be read through the notches. If, now, it is desired to add 8 units, the pencil is placed at 8 on the first slide but as the color has changed at the point designated, being no longer green, but white, this is a signal to the operator to move the slide to the right until the stylus strikes the right hand plate, and this movement to the right is always to be followed by moving the slide of next higher denomination one step to the left, to carry one to that denomination. Thus in the instance given (Fig. 1) the lug at 8 is to be carried to the right, and the next slide moved one step to the left with the result that 640 will then appear at the

sight notches. To subtract, the casing is reversed end for end, the same margin remaining directed towards the operator, and the procedure is then precisely as for addition, 5 care being taken, as in that computation, to reverse the lateral movement for the opposite colors, and whenever there is a right hand movement there must be a corresponding carrying to the next column. It will frequently 10 happen that all the slides will show a light color when it is necessary to carry 1 to that column. In such case the same rule holds, the pencil is moved to the right until it strikes the stop plate, and then is carried 15 to the next higher denomination, and if the 1 of that slide is also white the movement is also to the right and so on until a slide is reached in which 1 appears in a dark or left hand color, when the movement is again to 20 the left. Considering the left hand movements as positive, and the right hand ones as negative, we may formulate the following rule: When the stylus is placed upon a dark color the movement must be positive, and 25 when upon a light color the movement must be negative, every negative movement being a reminder to carry to the next higher denomination.

It is obvious that many changes may be 30 made in the details of construction of my invention as herein disclosed without departing from the spirit and scope thereof and I do not wish, therefore, to be limited to the precise form of the device illustrated.

Having thus described my invention, what 35 I claim as new, is:—

1. In a computing device, a suitable casing having openings therein, a series of numeral bearing bars fixed in said casing, each 40 of said bars having a single opening in its face and provided with a longitudinal groove upon one side, a series of numeral bearing bars slidably mounted in said casing and arranged alternately with said fixed bars, each

of said slidable bars having a ridge engaging 45 said groove in the adjacent fixed bar, the numerals on said slidable bars being positioned so as to be exposed only at the openings in the fixed bars, means for moving the slidable bars, and means for limiting the 50 movement of said bars.

2. In a computing device, a suitable casing, having openings therein, a series of numeral bearing bars fixed in said casing, each of said bars having an opening in its face, 55 and provided with a longitudinal groove upon one side, a series of bars slidably mounted in said casing, each of said bars having a longitudinal ridge engaging the groove in the adjacent fixed bar, and provided with a series of numerals and a series of spaced abutments upon opposite faces, and the numerals so arranged relative to the fixed bars as to be exposed only at the openings in said bars, and means for limiting the 60 movements of the slidable bars.

3. In a computing device, a suitable casing having openings therein, a series of bars fixed in said casing and bearing numerals on their opposite faces, each of said bars having 70 a longitudinal groove coextensive with the bar, and provided with a rounded notch and also furnished with a recess, a spring detent secured in said recess, a series of bars slidably in said casing and bearing numerals 75 upon their opposite faces, said numerals so arranged as to be exposed at the notches in the fixed bars, said slidable bars having spaced notches in one edge adapted to be engaged by said spring detents, and spaced 80 abutments arranged upon opposite sides of said slidable bars.

In testimony whereof I affix my signature in the presence of two witnesses.

JOSHUA TERRY JACKSON.
